TOOLHOLDER

Alfred Erickson, Chicago, Ill.

Application May 21, 1942, Serial No. 443,950

6 Claims. (Cl. 82—35)

My invention relates to cutting-off tools as used in lathes and similar machines, and more particularly to holders for such tools, and my main object is to provide a holder which prevents the tool from becoming jammed or deformed by the resistance of the work.

A further object of the invention is to provide a tool of the above character which uses the work as a basis or support to maintain it at the proper cutting level.

Another object of the invention is to provide a holder with positive means for resisting the rotative tendency of the work to crowd or jam the tool.

A still further object of the invention is to provide a tool holder which adapts itself to the running course or characteristic of the work, whereby to be in harmony with the same.

Another object of the invention is to design the novel tool holder along lines of simplicity, ease of control and adjustment and direct adaptability to the conventional tool post of the lathe.

With the above objects in view and any others which may suggest themselves from the description to follow, a better understanding of the invention may be had by reference to the accompanying drawing, in which—

Figure 1 is a side elevation of the novel tool holder, illustrating its application;

Fig. 2 is a plan view of the holder and tool; enlarged and partly broken away;

Fig. 3 is a front end view of the same; and

Fig. 4 is a fragmental section of the same taken on the line 4—4 of Figure 1.

Referring specifically to the drawing, a conventional cutting-off tool is shown at 10 and a typical piece of work at 11, full lines in Figure 1 indicating that the tool has cut into the work to a considerable extent.

Ordinarily, a cutting-off tool is held in a box-clamp supported by the conventional tool post. However, the improved holder makes the box-clamp unnecessary, since the holder is directly clamped in the tool post as will be explained.

The holder is primarily built with a base 12 extended rearwardly with a tail piece 13. The latter receives a bar 14 along one side, while the base and tail piece are recessed in the other side—as indicated at 15—to seat the tool 10 to a depth slightly less than its thickness.

The tail piece 13 receives the sunken head 16 of a bolt 17, which extends through the bar 14 to receive a securing nut 18. A fibre washer 18a is 55

interposed between the tail piece and the bar in the region of the bolt.

The base 12 receives a flat, approximately square block 19 on the side corresponding to the bar 14, and a similar block 20 on the opposite side. The block 20 is vertically recessed along its inner face, as indicated at 21, to seat a post 22 to a depth slightly less than its thickness, the upper portion of the post being extended with a forward finger 23. While the bottom of the latter is horizontal, the top tapers to a rounded extremity, as indicated at 24, for compactness and to save metal.

When the base and blocks are assembled as shown, the tool 10 and post 22 make contact in the area of their intersection; and in order to retain the tool and post, the base and blocks are bound together by a set of bolts 25 applied to the corner regions of the assembly. Thus, while the block 19 and base 12 are bored in alignment at 26 and 27 for the free passage of the bolts, the block 20 is tapped in continuation of these bores for the end portions of the bolts 25 to thread into the block 20. The adjustment of the bolts is such that the tool 10 and the post 22 are disposed in snugly sliding relation in the assembly of the base and blocks.

When the tool is to be put in use, the bar 14 is simply slid into the tool post 28 of the lathe and the set screw 29 thereof tightened when the approximate initial position of the tool in relation to the work is determined. The tool is then adjusted to contact the work 11 in the manner indicated by finely-dotted lines in Figure 1. Such lines also indicate that the finger 23 of the post 22 reaches to a point over the center of the work. The vertical adjustment of the post is intended to adapt the finger 23 to over-lie the work, whatever the initial diameter of the same may be. The finger will thus be of a sufficient length to reach to the top center, or beyond the top center, of work within a given range of sizes, it being essential in all instances that the finger over-lie the topmost region of the work. When the assembly has been arranged as in Figure 1, but with the tool 10 and post 22 in the initial positions as indicated by finely-dotted lines, the adjustment may be fixed by the application of a suitable key-wrench (not shown) to a socket screw 30 threaded from the outside into the block 19, as clearly shown in Fig. 4, such socket screw acting by its pressure upon the base 12 to retract the block 19 and draw on the block 20 through the agency of the bolts 25 to clamp the tool 10

and post 22 to the said base. It is thus possible to adjust the positions of the tool and the post finger 23 to the position and size of the work 11 by the simple and powerful control of the socket screw 30.

Since the tool 10 is at one side of the finger 23, it will be obvious that the latter remains on top of the work while the tool advances and proceeds with the cutting-off operation, so that the tool can at no time be influenced or forced downwardly by the rotative tendency or pressure of the work—as suggested by the arrow in Figure 1—when a heavy cut is taken. The post finger 23 therefore acts as a positive suspension for the tool, using the work to counteract its own tendency to jam or deform the tool.

The holder is also adjusted by means of the nut 18 to allow a limited pivotal motion on the part of the tool assembly in relation to the supporting bar 14, the intermediate washer 18a providing only sufficient play for the said assembly to descend of its own weight in relation to the bar. Thus, the finger rests on the work 11 at all times, and the tool accommodates itself to any fluctuations or eccentricities in the rotation of the work.

It will be evident from the above description that I have provided a holder for cutting-off tools which allows for horizontal, vertical and pivotal adjustments of its vital elements while grouping the parts of the holder into a neat and compact assembly. Further, this assembly is in the nature of a unit quickly and easily adaptable to the standard tool post of the lathe, so that its connection to the same should be self-evident even to a novice. Finally, the novel holder is an assembly of few and simple parts which are devoid of complications and do not require undue skill or accuracy for the production of the holder, so that the same becomes a useful and desirable piece of equipment in conjunction with the lathe or other machine to which it may be applied.

While I have described the novel tool holder along specific lines, it is apparent that minor changes or refinements may be made therein without departing from its principle. Thus, it may be used with a tool for radius or lateral cutting, with the finger 23 modified to retain its height along the original or basic portion of the work during travel and so keep the cutting edge of the tool at center level. This and other modifications are feasible to the skilled artisan and should be within the scope and spirit of the appended claims.

I claim:

1. A holder for a cutting-off or similar tool applicable at center level to work rotatable in a

lathe, comprising a supporting base receiving the tool on one side, a block applied to the remote side of the tool, a post rising between the block and the tool with a substantially horizontal projection positioned to rest on a portion of the work laterally of the cutting path, a companion block on the other side of the base, means to bind the blocks to the base to retain trial longitudinal adjustments of the tool and post, and means carried by the companion block to fix said adjustments.

2. A holder for a cutting-off or similar tool applicable at center level to work rotatable in a lathe, comprising a supporting base receiving the tool on one side, a block applied to the remote side of the tool, a post rising between the block and the tool with a substantially horizontal projection positioned to rest on a portion of the work laterally of the cutting path, a companion block on the other side of the base, means to bind the blocks to the base to retain trial longitudinal adjustments of the tool and post, and means carried by the companion block to simultaneously urge the base and the first-mentioned block toward each other and fix said adjustments.

3. A holder for a cutting-off or similar tool applicable at center level to work rotatable in a lathe, comprising a supporting base receiving the tool on one side, a block applied to the remote side of the tool, a post rising between the block and the tool with a substantially horizontal projection positioned to rest on a portion of the work laterally of the cutting path, a companion block on the other side of the base, means to bind the blocks to the base to retain trial longitudinal adjustments of the tool and post, and means carried by the companion block to simultaneously draw the first-mentioned block toward and push the support from the companion block, whereby to clamp the tool and post and fix said adjustments.

4. The structure of claim 1, said means to bind

comprising a set of bolts freely directed through the companion block and the support to thread into the first-mentioned block.

5. The structure of claim 1, said means to fix comprising a screw threaded into the companion block to bear against the support.

6. The structure of claim 1, said means to bind comprising pairs of bolts freely directed through the companion block and the support clearing opposite edges of the post and tool to thread into the first-mentioned block, and said means to fix comprising a screw threaded into a substantially medial portion of the companion block to bear against the support.

ALFRED ERICKSON.
